Primary Examiner—Susan J. Lucas
Attorney, Agent, or Firm—Terry M. Gernstein**[57] CLAIM**

The ornamental design for a combined electrical switch and battery powered night light, as shown and described.

DESCRIPTION

FIG. 1 is a front, top and side perspective view of the combined electrical switch and battery powered night light showing my new design;

FIG. 2 is a front elevational view thereof;

FIG. 3 is a rear elevational view thereof;

FIG. 4 is a side elevational view thereof, the side opposite being a mirror image of the side shown in FIG. 4.

FIG. 5 is a top plan view thereof; and,

FIG. 6 is a bottom plan view thereof.
